UNITED STATES PATENT OFFICE.

THOMAS H. RUSSUM, OF BALTIMORE, MARYLAND.

METAL VESTIBULE-DIAPHRAGM.

1,157,182.

Specification of Letters Patent. Patented Oct. 19, 1915.

Application filed February 12, 1915. Serial No. 7,819.

To all whom it may concern:

Be it known that I, THOMAS H. RUSSUM, a citizen of the United States, and a resident of Baltimore, Maryland, have invented certain new and useful Improvements in Metal Vestibule-Diaphragms; and I do hereby declare that the following is a full, clear, and exact description of the same, reference being had to the accompanying drawings, and to the numerals of reference marked thereon, which form a part of this specification.

A great source of expense and trouble in the proper maintenance of rolling stock for passenger traffic is the so-called vestibule diaphragm connected at each end of the cars. In the past such diaphragms have generally been of the accordion type, which have consisted of heavy ply fabric folded or stitched in various ways to form an expandable structure. It is essential in this type of device that not only a weatherproof construction be provided, but also one not liable to rattle and become noisy when subjected to the hard service required. Heretofore the most successful type of noiseless vestibule diaphragm has been that made of fabric or other similar material, but these have proved expensive to manufacture and maintain.

This invention, however, relates to a telescoping metal diaphragm constructed to be effectually sealed in various positions of adjustment, thoroughly impregnable to the weather, and, as well, operating noiselessly.

It is an object therefore of this invention to construct a telescoping metal car diaphragm embracing metal sections slidably mounted one upon another and bearing resiliently against one another upon suitable sealing means so as to permit warping movements of the diaphragm to take place without causing an opening to occur between the parts and also insuring silence of operation.

It is also an object of this invention to construct a car diaphragm comprising a fixed arched section rigidly secured on the end of a car with a larger similarly shaped section fitted thereover and adapted to telescope thereon, the top and side members of said latter member being flexibly mounted, and having resilient means associated therewith to cause the same to bear yieldably upon said fixed arched section.

It is also an object of this invention to construct a telescoping car vestibule diaphragm embracing sections interfitting with

one another and having a sealing strip inserted therebetween with resilient mechanism for holding the sections associated with said sealing strip compressed therebetween. 60

It is furthermore an important object of this invention to construct a telescoping car vestibule diaphragm made up of metal sections and with resilient means associated therewith to hold said metal sections impelled against one another in sealing relation. 65

It is finally an object of this invention to construct an improved type of car vestibule diaphragm consisting of few parts made of metal so as to be impervious to the weather and possessing many advantages of durability over constructions heretofore used. 70

The invention (in a preferred form) is illustrated in the drawings and hereinafter 75 more fully described.

In the drawings: Figure 1 is a fragmentary side elevation partly broken away and shown in section illustrating a car vestibule diaphragm embodying the principles of my 80 invention. Fig. 2 is a section taken on a horizontal plane at the end of a car with a vestibule diaphragm embodying the principles of my invention attached thereon. Fig. 3 is a fragmentary detail section taken on 85 line 3—3 of Fig. 1. Fig. 4 is a detail section taken on line 4—4 of Fig. 3. Fig. 5 is a view of a modification of my invention.

As shown in the drawings: The reference numeral 1, indicates as a whole the end platform of a car having a vestibule platform extension 2, and end walls 3, which extend vertically from the sides of the car toward the vestibule extension of the platform in convergent relation. An arched opening is 90 afforded between said respective convergent end walls 3, of the car, and secured thereover is a rigid arched stationary vestibule section 4, having an extending flange 5, therearound by which the said member is 100 attached to the end walls 3. Said vestibule section 4, may be of a single unitary piece of metal formed to the required shape, or may be built up of members secured to one another, if so desired. Fitted slidably over 105 said arched vestibule section 4, is a similarly shaped outer section consisting of a curved top piece 6, and straight side members 7, and joined to said curved top piece 6, are stiff leather or fabric aprons 8, which extend 110 downwardly and overlap the upper ends of the side members 7. Said curved top piece

6, and side members 7, are all positively supported upon the face plate 9, of the vestibule, said top and side members being hingedly connected thereto by hinges 10 and 11, respectively. As stated, the sectional outer telescoping section of the vestibule fits over and around the stationary section 4, and the respective hinged members of said telescoping section are normally impelled 10 inwardly closely upon and toward said stationary arched section by means of springs 12, which are associated with said respective hinged members 10 and 11. Interposed between the spring impelled members 6 and 7, 15 of the outer vestibule section and the inner stationary section 4, is a strip of felt or other weatherstripping material 13, which may be attached to either one of the telescoping sections constituting the vestibule, 20 but as shown is secured near the edge of said stationary arched section on the exterior thereof, thus sealing the space between said respective sliding sections.

In the modification illustrated in Fig. 5, 25 I have shown a stationary vestibule section 19, similar to the section 4, previously described, and secured to the face plate 9, is a resilient plate 20, bearing at its inner end against the weatherstripping element 21, secured 30 on the inner surface of the stationary section 19.

The operation is as follows: The relative movement permitted between the respective stationary and movable vestibule sections is 35 one telescopic in action, but due to the fact that the movable section is made up of a plurality of members which are resiliently impelled into weathertight contact with the stationary section, a certain amount of angular movement is permitted which is necessarily imposed upon the device when the 40 train is in motion. The vestibule face plate upon which the respective top and side members of the movable vestibule section are connected, affords a substantial support 45 therefor. The resilient contact between the movable member and the stationary member of the diaphragm affords not only a weather-tight construction, but also one silent in operation and free from objectionable 50 noise and rattling when the train is in motion.

The operation of the device constructed according to the modification illustrated in

Fig. 5 is practically identical, that is, a stationary vestibule member is provided which coacts with a movable member. As shown in Fig. 5, the movable member is provided with resilient members which bear against the weatherstripping element on the stationary section. 55 60

I am aware that various details of construction may be varied through a wide range without departing from the principles of this invention, and I therefore do not 65 purpose limiting the patent granted otherwise than necessitated by the prior art.

I claim as my invention:

1. In a vestibule diaphragm of the class described, a stationary section, a section telescoping therewith at top and sides, and means holding one of said sections yieldably against the other section at all points. 70

2. In a vestibule diaphragm of the class described, a stationary section, a section telescoping therewith at the top and sides, and means holding said latter section yieldably against said stationary section at all points. 75

3. In a vestibule diaphragm of the class described, an inner stationary section, an outer section fitting thereover at the top and sides and adapted to slide thereon, said outer section comprising a plurality of spring impelled members bearing yieldably upon the outer surface of said inner member 80 85 at all points.

4. In a device of the class described, the combination with a stationary section comprising top and sides, of a similar movable section interfitting therewith, and hinged connections on the top and side of said movable section spring-pressed toward said stationary section to permit an angular movement between said sections. 90

5. In a device of the class described, a stationary inverted U section, and a movable inverted U section coacting therewith, said movable section comprising top and side hingedly mounted spring-pressed members movable independently of one another. 95 100

In testimony whereof I have hereunto subscribed my name in the presence of two subscribing witnesses.

THOMAS H. RUSSUM.
